UNITED STATES PATENT OFFICE.

JOHN W. PERKINS, OF PORT NORFOLK, VIRGINIA.

RAILWAY-CROSSING.

1,082,607.

Specification of Letters Patent.

Patented Dec. 30, 1913.

Application filed February 21, 1913. Serial No. 749,848.

To all whom it may concern:

Be it known that I, JOHN W. PERKINS, a citizen of the United States of America, and resident of Port Norfolk, in the county of 5 Norfolk and State of Virginia, have invented certain new and useful Improvements in Railway-Crossings, of which the following is a specification.

This invention relates to certain new and 10 useful improvements in railway crossings and pertains more particularly to a continuous railway crossing and while designed more particularly for street railways, it will be evident as the description proceeds that 15 it is in no wise confined to street railway traffic.

The present invention has for its object among others to provide a simple and improved form of continuous railway crossing 20 composed of few parts, those readily assembled and reliable and efficient in use and not liable to get out of repair. I so construct and arrange the parts that no frogs are necessary and the line is normally 25 closed, the movable members at the angles of the crossing being arranged to overlap and normally closed, the construction and arrangement of parts being such as to avoid or prevent pounding as the wheels of the 30 train pass over the points of intersection of the rails, the result being that all noise generally incident to crossings is practically eliminated.

I aim further at the accomplishment of 35 such other ends as are usually sought in this class of devices.

Other objects and advantages of the invention will hereinafter appear and the novel features thereof will be particularly 40 pointed out in the appended claims.

While the structural embodiment of the invention as herein disclosed is what I at the present time consider preferable, it is evident that the same is subject to changes, 45 variations and modifications in detail, proportion of parts etc., and I, therefore, do not intend to restrict myself to the exact construction herein disclosed, but reserve the right to make such changes, variations and 50 modifications as come properly within the scope of the protection prayed.

The invention is capable of embodiment in a variety of forms, the preferable ones of which only I have chosen to herein illustrate.

The invention in its prefererd form is

clearly illustrated in the accompanying drawings, which, with the numerals of reference marked thereon, form a part of this specification, and in which—

Figure 1 is a plan view of a railway crossing illustrating my present improvement. Fig. 2 is a vertical cross section on the line 2—2 of Fig. 1, looking in the direction of the arrows. Fig. 3 is a similar section on the line 3—3 of Fig. 1. Fig. 4 is a similar section on the line 4—4 of Fig. 1. Fig. 5 is a similar section on the line 5—5 of Fig. 1. Fig. 6 is a vertical cross section on the line 6—6 of Fig. 1. Fig. 7 is a perspective view of one of the movable members. Fig. 8 is a perspective view of the other movable member. Fig. 9 is a vertical cross section similar to Fig. 5, showing a slight modification.

Like numerals of reference indicate like parts throughout the different views.

Referring to the drawings, 1 designates what may be termed the main line track which, in the present instance, is shown as open, that is with the parts in position when a train is passing over the same in the direction of the arrow in Fig. 1.

2 is the track at right angles thereto and which, in Fig. 1, is shown with the movable members closed, it being understood that normally, that is when a train is passing, the movable members of the main line track will also be closed.

At the outer corner of each angle of the crossing I provide the angular member 3 and between said members the rail portions 4 are disposed. These rail sections midway between the angles are given the form of the usual rail, as seen best at 5 in Fig. 6, 95 and indicated by dotted lines in Fig. 1. These sections 4 each has connected therewith a clean-out box 6 with a cover plate 7 of any preferred construction and each of the members 4 is provided with a horizontal lug 8, as seen best in Fig. 5, having an opening 9 in which is received the stud or member 10 depending from the movable member 11, a nut 12 usually being employed, as seen in Fig. 5 upon the lower end of said member 10 for an obvious purpose. This member 11 has movement in the recess 13, the opposite walls 14 and 15 of which serve to limit the movement of the said member 11, as will be evident upon reference to Fig. 110 5. The wall 15 tapers, as seen in Fig. 1, being thicker, as seen at 15^a, as it approaches

the angle of the crossing, the member 11 tapering correspondingly. In Fig. 9 I have shown a spring 16 around the pivot or pindle 10 confined between the nut 12 on said pin and the under side of the lateral extension or projection 8^a which, in this instance, is thinner than the corresponding portion 8 in Fig. 5, so as to provide room for the spring to allow of the necessary vertical movement of the pin and the member 11, as will be readily understood. These boxes 6 serve as clean-out boxes, access being had thereto by removal of the cover plates 7, as will be readily understood.

Each member 4 is provided with a recess 17, as seen best in Fig. 1, for the reception of the lug 18 on the member 11, the square face or shoulder 19 thereof engaging the corresponding walls of said recess, as will be evident from an inspection of Fig. 1. The member 11 is provided with a depression or cut-away portion 20, as seen best in Fig. 7, to allow of the passage of the flange of the wheel. The member 22 is provided with a pin or pindle 23 received in an opening in the right-angled portion of the adjacent member 4, as seen in Fig. 1. This member 22 has the lateral lug 24 received in the adjacent recess 17 of the adjoining member, as seen in Fig. 1, and is provided with the depression or channel 25, as seen in Fig. 8, in which the reduced end portion 21 of the member 11 is received and adapted to slide, it being understood, as will be seen in Fig. 1, that the free end portions of the members 11 and 22 cross each other, these parts being arranged one above the other, so as to allow freedom of movement of each. The free ends of the members 11 and 22 are curved inwardly, as seen in Fig. 1, for an obvious purpose.

Within the inner angles of the crossing are the boxes 26 having cover plates 27 and within each box 26 is secured an angular member 28 in any suitable manner. 29 are pins working loosely through the angular walls of this angular member, springs 30 being arranged around each pin, as seen in Fig. 1, and the pins projecting through the adjacent walls of the box, the extended end of each pin being in contact with the adjacent free end of one of the members 11 or 22, as seen in Fig. 1. Suitable nuts 31 are provided for adjustment of the springs as occasion may require. Normally these springs tend to force the free ends of the members 11 and 22 outward, so that the lines are closed, but when a passing train comes to the crossing, the flange of the wheel enters between the member 3 and the adjacent face of the member 11 or 22 and forces the same out or away from the member 3, compressing the spring, and as soon as the train has passed, the springs force the members back 65 into closed position. The members 11 and

22 are automatically moved to open position by the passing train and are automatically returned to closed position by the springs. The parts are few in number, not readily tampered with, require no attention on the part of the engineer or other person and are not readily affected by any atmospheric conditions. Parts may be used without the whole and some parts may serve effectively in connection with other parts of a form different from that herein disclosed.

What is claimed as new is:—

1. In a continuous railway crossing, angular rail members at the angles of the crossing, intermediate rail members, pivoted members extended at right angles to each other and overlapped at the inner angles of the crossing, and means disposed at right angles to each other and independently acting on the free ends of said pivoted members to normally hold them in closed position.

2. In a continuous railway crossing, angular rail members at the angles of the crossing, intermediate rail members, pivoted members extended at right angles to each other and overlapped at the inner angles of the crossing, and means disposed at right angles to each other and independently acting on the free ends of said pivoted members to normally hold them in closed position, said intermediate rail members and the pivoted members having interengaging recesses and projections.

3. In a continuous railway crossing, angular rail members at the angles of the crossing, intermediate rail members, pivoted members extended at right angles to each other and overlapped at the inner angles of the crossing, and means disposed at right angles to each other and independently acting on the free ends of said pivoted members to normally hold them in closed position, said intermediate rail members and the pivoted members having interengaging recesses and projections, and the overlapping portions of the pivoted members movable one upon the other.

4. In a continuous railway crossing, independently pivoted members overlapping each other at the inner angles of the crossing, a housing, a fixed member therein, and spring controlled members supported by said fixed member and disposed at substantially right angles to each other independently of each other and acting upon the free ends of the pivoted members.

5. In a continuous railway crossing, angular rail members at the angles of the crossing, intermediate rail members having recesses, and independently pivoted members extending at right angles to each other and having projections co-operating with said recesses, the said pivoted members overlapping each other at the inner angles of the crossing and an independent spring for 130

- each of said pivoted members, arranged at substantially right angles to each other, and an angular member common to both of said springs and against which they bear.
- 5 6. In a continuous railway crossing, angular rail members at the angles of the crossing, intermediate rail members having recesses, and independently pivoted members extending at right angles to each other and
- 10 having projections coöoperating with said recesses, the said pivoted members overlapping each other at the inner angles of the crossing and having sliding engagement with each other and an independent spring
- 15 for each of said pivoted members, arranged at substantially right angles to each other, and an angular member common to both of said springs and against which they bear.
7. In a continuous railway crossing, angular rail members at the angles of the crossing, intermediate rail members having recesses, independently pivoted members extending at right angles to each other and having projections coöoperating with said recesses, the said pivoted members overlapping each other at the inner angles of the crossing and having sliding engagement with each other, and spring means acting independently upon and normally holding the free ends of said pivoted members in
- 20 closed position.
- 25 8. In a continuous railway crossing, an-
- gular rail members at the angles of the crossing, intermediate rail members having recesses, independently pivoted members ex- 35 tending at right angles to each other and having projections coöoperating with said recesses, the said pivoted members overlapping each other at the inner angles of the crossing and having sliding engagement 40 with each other, and spring means normally holding the free ends of said pivoted members in closed position, said spring means acting independently on each pivoted member and arranged at right angles to each 45 other and to said pivoted member.
9. In a continuous railway crossing, a rail member having horizontal projection and recess, and a pivoted member supported on said projection and movable in said recess. 50
10. In a continuous railway crossing, a rail member having horizontal projection and recess, and a pivoted member supported on said projection and movable in said recess, the pivot of said member being capable of vertical movement and normally held in closed position by yielding means. 55

Signed by me at Portsmouth, Va., this 18th day of February 1913.

JOHN W. PERKINS.
